UNITED STATES PATENT OFFICE.

BENJAMIN F. MAYO, OF SALEM, MASSACHUSETTS, ASSIGNOR TO UNITED SHOE MACHINERY COMPANY, OF BOSTON, MASSACHUSETTS, A CORPORATION OF NEW JERSEY.

EDGE-TRIMMING MACHINE.

No. 798,617.

Specification of Letters Patent.

Patented Sept. 5, 1905.

Application filed August 31, 1900. Serial No. 28,697.

To all whom it may concern:

Be it known that I, BENJAMIN F. MAYO, a citizen of the United States, residing at Salem, in the county of Essex and State of Massachusetts, have invented an Improvement in Edge-Trimming Machines, of which the following description, in connection with the accompanying drawings, is a specification, like characters on the drawings representing like parts.

My invention in edge-trimming machines is herein shown as embodied in a machine for trimming the edges of the soles of shoes, the object of the invention being the production of a rapid machine to trim the edges uniformly and insure smooth edges about the ball, sides, and toe, the invention being especially useful on shoes having toe-caps or on shoes unevenly and poorly lasted, so that the upper presents wrinkles or bunches where it overlaps the inner sole.

This invention constitutes an improvement on the invention shown in application for United States Letters Patent, Serial No. 7,255, filed by me March 3, 1900.

One important feature of my invention resides in the employment of an elongated gage having contact-surfaces on each side of the point where the cutting is taking place. One end of said gage contacts with a trimmed portion of the sole, the opposite end of the gage contacting with the upper, that end being preferably curved that it may readily ride over the edge of the toe-cap or any irregularity in the surface of the upper. By means of a gage comprising these contact-surfaces located at opposite sides of the point where the cutting is taking place and at some distance from that point I am able to reduce to a minimum the variations which are commonly caused in the contour of the trimmed sole by irregularities in the surface of the shoe with which the gage contacts in guiding the shoe with relation to the cutter.

Another feature of the invention consists in providing a gage adapted to engage the sole edge and the upper at points distant from the place where the cutter acts and on the opposite sides of the plane in which the face of the cutter rotates.

By the use of my invention shoes may be trimmed rapidly and uniformly and the trimmed edges may be cut smoothly and

without leaving swells or bunches on the sole edges opposite the inner ends of the toe-cap or opposite any enlargements or wrinkles in the upper due to unequal lasting or other causes such as are often left by the cutter when the gage is short and contacts with the upper close to the cutting-point.

The gage of my present invention is also an improvement over a gage having surfaces located on either side of the point where the cutting is taking place, but having both of said surfaces adapted to contact with the upper. By constructing my gage so that one of the contact-surfaces engages the sole at points where it has already been trimmed I do away with such variation in the position of the shoe with reference to the cutter as might result if the gage contacted only with the upper.

In addition to the two surfaces adapted to contact with the upper and the trimmed sole, respectively, I prefer to form my gage with a contact-surface located at substantially that part of the gage which is nearest to the point where the cutting is taking place and adapted to contact with the upper and guide the shoe when a very convex portion of the sole edge is being trimmed, such as the toe end of the sole.

The gage is preferably recessed to expose the work to the view of the operator at or near the point where the cutting is taking place.

Figure 1 in side elevation represents a trimming-machine embodying my invention in one of the best forms now known to me. Fig. 2 is a view, on a larger scale, of the upper part of the machine shown in Fig. 1 looking at it from the left. Figs. 3 and 4 are details to be referred to of parts shown in Fig. 2. Fig. 5 is a detail view of parts shown in Figs. 3 and 4 as seen from the section-line $a^3 a^5$, Fig. 9. Fig. 6 is a view, on a larger scale, of the right-hand side of the upper part of the machine shown in Fig. 1. Fig. 7 is a plan view of the parts shown in Fig. 6. Fig. 8 is a detail showing the pin b^6 . Fig. 9 is a section in the line 9-9, Fig. 7. Fig. 9^a is a detail to be described. Fig. 10, in two views, shows one form of my improved gage. Fig. 11 shows in two other views a modified form of gage. Figs. 12 and 13 show yet other modifications. Fig. 14 shows the gage of Fig. 12 in position on a shoe the sole of which is being trimmed.

Fig. 15 is a view looking at Fig. 14 in the direction of the arrow. Fig. 16 shows the advance end of the gage as having mounted the edge of the toe-cap, and Fig. 17 shows the relation of the shoe to the gage when the toe is being trimmed.

The framework consists, essentially, of a column A, having a foot A' to stand on the floor, the column supporting a head A², having uprights A³ A³ to hold bearings A⁴ for the cutter-shaft A⁵.

The shaft has clamped upon it by a screw A⁶ a belt-pulley A⁷, over which is passed a belt A⁸, driven from a belt-wheel A⁹, fast on a shaft A¹⁰, taking its bearing in the column and in a stand A¹⁰ and provided with a fast and a loose pulley A¹² A¹³, a suitable belt (not shown) when on the fast pulley A¹² driving the machine. The shaft A⁵ has connected with it by a screw a a recessed collar a', so that the shank a² of a feather-edger a³ may slide on the shaft, said shank being surrounded by a spring a⁴, slots in the shank being entered by guide-screws a⁵. The front end of the shaft is reduced to form a tenon, (see Fig. 9.) and the shaft is bored and threaded to receive a conical-headed screw a⁶, and the tenon and shaft are provided with a plurality of slots, so that as the said screw is turned into the threaded bore of the shaft the head will expand the tenon and cause it to center and hold in place the cutter a⁷, which may be of any usual or suitable construction. The outer end of the screw a⁶ is provided with a threaded hole to receive the threaded shank of a stud-screw a⁸, which receives and sustains the rand-guide a⁹, a backwardly-projecting annular portion of the rand-guide entering the hub of the cutter, which is not fully occupied by the screw a⁶.

The forward upright A³ has at its sides bosses B B', bored for the reception of guide-rods B² and B³, respectively. A cross-bar B⁵ is secured to the upper ends of the rods B² B³ by means of nuts B⁴. The cross-bar B⁵ has a central hub B⁶, which is bored substantially parallel with the cutter-shaft A⁵ to receive a rock-shaft B⁷. (See Fig. 9.) On the front end of the rock-shaft is loosely mounted a gage-carrier B⁸, which, as herein shown, has three arms b b' b''. The arms b' b'' carry gages adapted for use in trimming different parts of a shoe, and the rock-shaft may be moved to bring either of said arms b' or b'' into position to present the gage carried thereby in operative relation to the cutter.

The gage-carrier is adjustably secured in angular position and is adjusted longitudinally on the shaft B⁷ by the following means: b' indicates an arm extended from a collar adjustably secured to the shaft B⁷ by a set-screw b''. (See Figs. 6 and 7.) The arm b' has a lateral extension b³, which is received between two guide-lugs b⁵ b⁶ on the side of the arm b of the gage-carrier. By adjusting the collar

and arm b' about the shaft the gage-carrier B⁸ may be secured in the desired angular position on the shaft. A rod b⁶ is detachably secured at one end in the arm b' by a locking-pin b⁹, the rod being provided with a notch 3, 70 which is entered by the locking-pin. The locking-pin also has a notch b¹⁰, (see Fig. 8,) and the pin may be turned by means of a handle b¹¹ to bring said notch into alignment with the rod b⁶ to permit the rod to be removed from the arm b'. The rod b⁶ projects through an opening in the arm b of the gage-carrier B⁸, and said gage-carrier may be adjusted longitudinally of its shaft B⁷ by means of a nut b⁸, mounted on the screw-threaded 80 end 2 of the rod b⁶ and bearing against the arm b of the gage-carrier. The gage-carrier is held normally in its outermost position by a spring b⁷, which is seated in a socket in the arm b and surrounds said rod. The spring 85 bears at one end against said arm b, and at its other end against a collar 4 on the rod b⁶, as shown in Fig. 7. It will be understood that by operating the nut b⁸ the gage-carrier may be adjusted in a direction parallel with the 90 cutter-shaft to position the gages nearer to or farther from the cutter, according to the requirements of the work or the size of the cutter, and that by unlocking the rod b⁶ from the arm b' the gage-carrier may be removed entirely from the shaft B⁷ and from the machine.

The arms b' and b'' extend radially from the hub of the gage-carrier B⁸ and are bored in the direction of their length. The arm b' receives the upper end of a rod C³, provided at its lower end with a threaded hole in which is entered a screw C⁴, having an enlarged head beveled at one side (see Fig. 9) and located at the inner side of the rod C³, said screw being surrounded by a washer C⁵, beveled at one side, 105 the two bevels leaving a raceway for a series of balls 4, which are surrounded by a circular plate 5, grooved internally, to which is adjustably attached by a screw 6 the slotted shank of a gage D, to be described, which constitutes one of the chief features of this invention. The plate 5 turns freely on the balls, as provided for in my said application.

To adjust the gage vertically in the arm b' of the gage-carrier B⁸, so that its lower edge 115 may occupy normally the desired position with relation to the rand-guide, I have provided the upper portion of the rod C³ with a transverse slot, (see Fig. 9,) which is entered by a crank-pin 7 at the end of a shaft 8, having a hand-wheel 9, said shaft taking its bearing in a clamp 10, having a thread and screwed into a boss 12 on the arm b'. By turning the shaft 8 the rod C³ may be raised or lowered, and it may be clamped in its adjusted 125 position by turning in the clamp 10.

The rod C³ has a spring-pressed bolt 13, (see Fig. 9a,) contained in a cross-hole of the rod, which bolt contacting with the carrier acts as a friction device to hold the rod in po- 130

sition, except when turned positively by the adjusting device.

Fig. 10 shows two views of the gage D detached. The gage has a slotted shank d^1 , supporting at its lower end the foot, having the parts d^2 , d^3 , d^4 , and d^6 , said foot being preferably composed of metal which may yield when necessary in use. The gage is of considerable length, extending forwardly and backwardly from the central part d^6 , which is adjacent the point where the cutter does its work in trimming the sole edge. At the end d^6 this gage has a lip or projection d^2 , curved upwardly, as shown, the rounded lower side of the projection bearing on the edge of the sole after it has been trimmed and constituting a sole-edge gage. The opposite end d^3 of the gage bears on the upper near the sole or welt, and its end is upturned, so that it may easily ride over the rear edge of a toe-cap, as illustrated in Fig. 16, and so that it may readily pass over any other irregularity in the upper.

It will be observed that when the sides of the sole are being trimmed the lip d^2 and the opposite end d^3 of the gage contact with the edge of the sole and the upper, respectively, on opposite sides of the vertical plane in which the face of the cutter rotates, this being substantially the plane in which the rand-guide rotates in case a rand-guide is used, and that the point where the lip d^2 contacts with the sole is at some distance to the rear of where the cutter is working, while the point where the end d^3 engages the upper is at some distance in advance of the point where the cutter is operating. The central part d^6 of the gage is at this time preferably not in contact with any part of the shoe, being located in a plane slightly above the upper, while the shoe is guided by the parts d^2 and d^3 , so as to pass over irregularities in the guiding-surface of the upper without engaging said irregularities, whereby the shoe is guided by the parts d^2 d^3 of the gage while the side of the sole is being trimmed.

In Fig. 10 I have shown the part d^3 of the gage which runs on the upper next the sole as provided with a separate piece d^{3x} , attached to the body of the gage by screws 16, said piece being made of yielding material and having a lip d^4 , also to engage the edge of the sole, such lip being sometimes desirable—as, for instance, on patent-leather, to which the part d^3 of the gage has a tendency to adhere. Using the lip d^4 results in reducing the friction on the part d^3 and enables the shoe to be moved freely. In some classes of work, where the sole is rounded or shaped after it has been attached to the shoe, as in "Goodyear work," it is desirable to guide the shoe entirely by the edge of the sole when trimming the sole on the sides of the shoe, and in such work also the attachment d^{3x} is used.

The end d^3 is preferably integral with the

body of the gage, and the material of the gage may be more or less yielding, according to the work to be done, the gage being stiffer for heavy than for light work.

The lip d^4 may be made integral with the gage, as in Fig. 11, and for some work said lip may be omitted, as shown in Figs. 12 and 13, said figures differing only in that the metal used in the gage shown in Fig. 12 is thicker and stiffer than in Fig. 13, so that one is rigid and the other may yield, either being used as the necessities of the work require.

The edge 50 of the gage will preferably be shaped so as to form a guide to engage the welt or the upper surface of the sole next to the upper, and thereby assist in guiding the shoe. Said edge is preferably cut away somewhat along the central portion d^6 of the gage to accommodate the rand-guide and to permit the workman to see the edge being trimmed at and just ahead of the point where the cutter acts.

When the toe of the sole is being trimmed, the shoe is guided by contact of the upper with the central portion d^6 of the gage, as shown in Fig. 17, instead of being guided by contact of the upper and sole with the portions d^3 and d^2 , respectively, of the gage, as when trimming the sides. In order that the shoe shall be guided the right distance from the cutter to secure the desired relative amount of projection of the edge at the toe and at the sides of the shoe, the gage may be formed so that the central toe-guiding portion d^6 stands in a different plane from that in which the guiding portions d^2 and d^3 are located. This insures that the edge shall project the desired distance beyond the upper at the sides and at the toe, and as the shoe passes gradually from the guidance of the end portions of the gage to the guidance of the central portion d^6 as the trimming advances from the sides to the toe, or vice versa, no abrupt change occurs in the amount of projection obtained if the projection is different at the toe and at the sides.

Sometimes it is desired by an operator to trim the shank of the sole with the fore-part cutter, although usually a different cutter is employed for trimming the shank, and I have therefore attached to arm b^2 of the gage-carrier B⁸ a shank-gage E⁹. The arm b^2 is bored to receive the shank of the shank-gage E⁹, said gage being held in adjusted position by an eccentric shaft 14, having a head 15 and a clamp 16, these parts being the same in construction and operation as the corresponding parts 8, 9, and 10, employed for adjusting and securing the shank of the gage D, and heretofore described in detail.

I have provided means for locking the rock-shaft B⁷ in position to present the gage D in operative relation to the cutter, as shown in Figs. 2, 5, 6, and 9, and also means for unlocking the rock-shaft and turning it into po-

sition to present the shank-gage E⁹ to the cutter. The means for locking the rock-shaft comprises a collar E², fast to the rock-shaft and provided with a lug E⁶, adapted to coöperate with a latch E⁴. The latch E⁴ is carried by an arm D^{9X} of a collar D⁹, loose on a rod or shaft D⁴. The rod D⁴ is supported in an arm B^X, projected vertically from the bearing B⁶ of the rock-shaft, and is secured in said arm by a screw D³. A spring D⁷ for holding the latch E⁴ normally in engagement with the lug E⁶, is mounted on the rod D⁴ and has one end connected at D⁸ to the collar D⁹ of the latch-carrying arm D^{9X}, the other end of the spring being connected to the collar D⁶. The collar D⁶ is adjustably secured on the rod D⁴ by a screw D⁵. The means for disengaging the latch from the lug E⁶ of the rock-shaft and turning said shaft to present the shank-gage E⁹ in operative relation to the cutter comprises an elbow-lever E, carrying a stud D¹⁰ in the path of the latch-carrying arm D^{9X}. The elbow-lever E is connected at one end by a link E' to a lug E^{2X} on the collar E² of the rock-shaft. The connection between the link and the lug E^{2X} comprises a pin 112 on the lug, which moves freely in a slot 110 in the link. This provides for a limited amount of lost motion between the lever and the rock-shaft to permit the stud D¹⁰ on the lever to move the latch E⁴ out of engagement with the lug E⁶ on the rock-shaft before the lever becomes effective to turn the rock-shaft. The elbow-lever E is connected by a rod E⁷ to a treadle E⁸, Fig. 1, by which it is actuated to unlock and turn the rock-shaft to bring the shank-gage E⁹ into operative position. The first portion of the movement of the treadle E⁸ moves the elbow-lever and the latch E⁴ into the position shown in Fig. 3 to unlock the rock-shaft, the lost-motion connection 110 112 permitting this movement to take place without the rock-shaft being actuated. The continued movement of the treadle turns the rock-shaft and the gage-carrier B⁸ from the position shown in Fig. 3 to the position shown in Fig. 4 to move the gage D, supported in the arm b', out of operative position and bring the shank-gage E⁹, supported in the arm b², into operative relation to the cutter. This movement of the rock-shaft takes place against the tension of a returning-spring C, which when the treadle is released raises the treadle and restores the parts to their normal position with the gage D in operative relation to the cutter. The spring C surrounds the rock-shaft B⁷ and has one end secured to a collar C', which is fastened on the bearing B⁶. The other end of the spring is connected with the arm b⁴ of the rock-shaft, as shown in Fig. 6. The extent of the return movement imparted to the rock-shaft by the spring C is limited by a stop, shown as a loop E^{8X}, engaging the treadle E⁸ to limit its rise. This return movement is

just sufficient to permit the latch E⁴ to re-engage the projection E⁶ on the rock-shaft B⁷, after which the rock-shaft is locked from movement in either direction by the said latch and the stop E^{8X} and remains locked until the latch is again disengaged. 70

The width of the sole edge left after trimming is determined by the position of the gage with relation to the lower edge of the cutter, and to enable the workman to control the machine for trimming edges, which vary in width 75 at different parts of the shoe, I have made provision for raising and lowering the gage-supporting rock-shaft B⁷. I do this in the following manner: I surround the sliding shaft B³ with a spiral spring G, which rests 80 at its lower end on a nut G', screwed on said rod, the upper end of said spring meeting the part B' of the fixed framework, and I provide the rod B² with an adjustable stop-nut G². The spring acts to put the gage in its 85 lowest position, and when trimming a sole edge the operator may put his foot on a treadle G³, having attached to it a rod G⁴, connected with an arm G⁵, fast on a short rock-shaft G⁶, extended through the frame A², said shaft 90 (see Fig. 6, dotted lines) being notched at 22 near its opposite end, so that as said shaft is turned it will meet the lower end of the rod B³ and lift it and the gage, the extent of upward movement of the gage, and consequently 95 the maximum variation in the width of the different parts of the sole edge left after the trimming operation, being determined by the position of the stop-nut G² on the rod B². This nut may, however, be adjusted to provide 100 for any desired variation in width of the sole edge at different parts of a shoe.

In addition to the shank-gage adapted for use with the fore-part cutter, which enables the workman to trim the shank with the same 105 cutter with which he trims the fore part of the sole, I have equipped the present machine with the usual separate shank-cutter. The framework, as shown, has suitable bearings 110 for a shaft F, having at one end a belt-pulley F', which is driven by a belt F², in turn driven by a pulley F³, fast on the power-shaft A¹⁰. The other end of the shaft F is provided with a secondary rotary cutter F⁴ of usual construction, which may be used when necessary 115 to bevel, trim, or finish the shank of the sole. The cutter F⁴ is held on the shaft F by a screw 17, and to make it possible for the guard F⁵ to come close to the face of said cutter I have slotted said guard, as at 18, Fig. 2, said slot 120 being beveled at its inner side, thereby to adapt it to embrace closely the usual shield on the cutter. The guard F⁵ is connected by a screw 19 with one end of a short shaft F⁶, (see Fig. 9,) said shaft being represented as 125 flattened or slabbed at 20 to be acted upon by the end of a thumb-screw 21. The outer end of the shaft F⁶ is slotted (see Fig. 2) to

constitute a guideway for the reception of the upper end of the guard, the latter having a slot to provide for vertical adjustment.

In the operation of the machine the trimming is usually started at the junction of the sole edge with the incurve of the shank, and at the start the end d^3 of the gage contacts with the upper at a point behind the cap edge, if the shoe has a toe-cap. The cutter having engaged the sole edge, the operator (see Fig. 14) moves the shoe in the direction of the arrow 44, the action of the cutter being from the shank toward the toe, and after the trimming has been done for a short distance the lip d^2 meets the trimmed edge of the sole, and usually it becomes seated on a trimmed part of said edge before the end d^3 of the gage meets the cap edge. As already explained, the cutting-point is at such distance from the contact-surface d^3 that the movement of surface d^3 over an irregularity, such as the edge of the toe-cap, produces very little effect at the cutting-point. The yielding character of the gage enables the end portion d^3 to yield somewhat as it moves onto and over an irregularity in the surface of the upper, such as the edge of the toe-cap, and thereby reduces the displacement of the shoe relative to the cutter, caused by such irregularity. When the relatively short contact-surface d^3 of the gage passes beyond the edge of the toe-cap or other irregularity, the gage is no longer in contact with or affected by said irregularity. This is due to the obliquity relative to the shoe-upper of the plane in which the upper and sole-edge contacting surfaces d^3 d^2 of the gage are located and also to the central part d^6 of the gage being curved or bowed up, as described, and therefore when the cutter is acting on the part of the sole adjacent to the end of the toe-cap there is no interruption in the uniform smoothness of the edge which is formed. As the toe is reached the end d^3 leaves the upper, and shortly thereafter the lip d^2 leaves the sole edge and the shoe is guided by the central part d^6 of the gage while the toe is being trimmed. (See Fig. 17.) The location of said central part d^6 preferably in a different plane from that in which the contact-surfaces d^2 and d^3 are located gives the desired width of projection to the toe relative to that given to the sides of the sole. The trimming having been carried on about the toe, the end d^3 of the gage again contacts with the upper, and before the cutter arrives opposite the cap edge the lip d^2 at the other end of the gage also again preferably comes to a bearing on the trimmed sole edge. When the gage is provided with portions to engage both the upper and the edge of the sole in advance of the point where the cutter acts and it is desired to guide by the upper, as sometimes happens when trimming patent-leather shoes, the shoe is held against the

gage with sufficient force to cause the sole-edge-engaging portion to yield until the upper-engaging portion contacts lightly with the upper. This light contact of the gage with the patent-leather upper is sufficient to guide the shoe, but does not produce an objectionable amount of friction or mark the patent-leather.

The framework in practice will include a bracket H^x , provided with a suitable stud H , on which may be placed the hub of a cutter the blades of which are to be ground. For this grinding I provide an emery-wheel H' , driven by a belt H^2 from a pulley H^3 , fast on the rear end of the cutter-shaft A^5 . The stud H is made adjustable by a clamp-nut H^4 in a slot H^5 of an arm H^7 , pivoted at H^8 to the bracket H^x , said arm being held in any desired position by a clamp-nut H^9 on its pivot-pin H^8 . The arm H^7 may be adjusted about the pivot H^8 by an adjusting-screw H^{10} , the end of which is represented as abutting against a stop H^{12} on the side of the bracket H^x . (See Figs. 2 and 6.) The adjustment mentioned provides for cutters of varying diameters and enables the grinding to follow any desired bevel. Also when the arm H^7 has been moved from its normal position to enable a shank-cutter to be ground its normal position can be again found by the screw H^{10} , the prior adjustment of which will not have been disturbed. In this operation the screw H^{10} serves as a stop.

While I have shown my improved gage as comprising contact-surfaces formed on an integral gage member made of yielding material, it is to be understood that said contact-surfaces might be formed on parts which were non-integral and one or more of which might yield independently of the other parts.

I have shown and described my improved gage as used for guiding the shoe as it is presented to a rotary sole-edge trimmer; but the gage is applicable to other uses than that referred to, and my invention is not limited to the use of the gage in conjunction with any specific tool for operating on the work guided thereby, and while in certain of the annexed claims I have recited combinations of my gage with a cutter I desire it to be understood that any other tool for operating on the work which is guided by the gage is the equivalent in said combinations of the cutter referred to.

Having described my invention, what I claim as new, and desire to secure by Letters Patent, is—

1. In a machine of the class described, an edge-trimming cutter, and a gage having a contact-surface to engage the upper in advance of the cutting-point, and a contact-surface to engage the edge of the sole in the rear of the cutting-point.

2. In a machine of the class described, a cutter, combined with a gage having a contact-surface to engage the edge of the sole of

the shoe being trimmed, and having a contact-surface to engage the upper, said points of engagement being one in front of and the other in rear of the point where the cutter 5 acts on the sole.

3. In a machine of the class described, an edge-trimming cutter, a pivoted yielding gage having its ends extended for a considerable distance in front of and behind the cutting- 10 point, one end of said gage contacting with the upper and the other with the sole edge.

4. The combination with an edge-trimming cutter, of a gage having contact-surfaces to engage the shoe in front of and behind the 15 cutter, one of said contact-surfaces engaging the edge of the sole and the other contact-surface engaging the upper.

5. The combination with an edge-trimming cutter, of a gage shaped to act against the sole 20 edge and the upper at a distance from the cutting-point and at the opposite sides of the plane in which the face of the cutter rotates.

6. In a machine of the class described, an edge-trimming cutter, a gage extended forwardly and backwardly from the cutting-point, one end of said gage being extended across the plane in which the face of said cutter rotates to rest on a trimmed part of the sole edge, the opposite end of said gage contacting with the upper at a point adjacent to 25 an untrimmed part of the sole.

7. In a machine of the class described, a cutter, a rand-guide and a gage having contact-surfaces to engage the upper and the edge 30 of the sole, and also a surface to engage the side of the sole adjacent to the upper.

8. In a machine of the class described, an edge-trimming cutter, and a gage having contact-surfaces to engage the shoe in front of and behind the cutting-point, one of said contact-surfaces engaging the edge of the sole and the other contact-surface engaging the upper, said gage also having a guide to engage the side of the sole adjacent to the upper. 40

45 9. In a machine of the class described, a rotatable cutter, a gage extended forwardly and backwardly from the cutting-point of the cutter, one end of said gage being extended across the plane in which the face of the cutter rotates to rest on a trimmed part of the sole edge, the opposite end of said gage contacting with the upper at a point adjacent to an untrimmed part of the sole, said gage having a face to engage the side of the sole next 50 to the upper.

10. In a machine of the class described, a gage having contact-surfaces to engage the upper and also the edge of the sole said gage being recessed to expose the work to the view 55 of the operator.

11. In a machine of the class described, a rotatable cutter, a gage extended forwardly and backwardly from the cutting-point of the cutter, one end of said gage resting on the sole edge, the opposite end of said gage bearing 60

ing on the upper, said gage being recessed to expose the work to the view of the operator.

12. In a machine of the class described, an edge-trimming cutter and a gage having contact-surfaces to engage the shoe in front of and behind the cutting-point, one of said contact-surfaces engaging the edge of the sole and the other contact-surface engaging the upper, the portion of the gage engaging the upper being curved. 75

13. In a machine of the class described, a rotatable cutter, a gage extended forwardly and backwardly from the cutting-point of the cutter, one end of said gage resting on a trimmed part of the sole edge, the opposite end thereof contacting with the upper at a point opposite an untrimmed part of the sole, said gage being curved in the direction of its length, whereby only the ends of the gage 80 may contact with the work, leaving the portion of the gage between the ends out of contact with the work. 85

14. In a machine of the class described, a rotatable cutter, a circular raceway, a carrier surrounding said raceway, and a gage connected with said carrier, said gage being shaped at one end to act on the edge of the sole and at the other end to act on the upper at a distance from the cutting-point of the cutter. 90

15. In a machine of the class described, an edge-trimming cutter and a gage having a contact-surface on one side of the cutting-point to engage the upper, and having a contact-surface on the other side of said cutting-point 100 to engage the edge of the sole, and means to adjust said gage. 95

16. In a sole-edge-trimming machine, a rotary cutter, and an edge-gage having a contact-surface engaging the upper in advance of the cutting-point and a contact-surface engaging the edge of the sole in the rear of the cutting-point, the portion of the gage contacting with the upper being free to yield to any inequalities in the stock. 110

17. In a machine of the class described, an edge-trimming cutter and a gage having a contact-surface on one side of the cutting-point to engage the upper, and having a contact-surface on the other side to engage the edge 115 of the sole, and means to vary the position of said gage while the sole is being trimmed to vary the width of the sole.

18. The combination, with an edge-trimming cutter, of a gage having guiding-surfaces to contact with the upper of the shoe being trimmed in advance of the point where the cutter acts and to contact with the edge of the sole in advance of the point where the cutter acts. 120

19. The combination, with an edge-trimming cutter, of a gage having a portion to engage the edge of the sole in advance of the point where the cutter acts, and also a portion to engage the upper in advance of the 130

- point where the cutter acts, said two portions being yieldingly connected, whereby they may adapt themselves to the varying distances between surfaces to be engaged.
20. The combination, with an edge-trimming cutter, of a gage having a portion to engage the upper and the edge of the sole of the shoe being trimmed in advance of the point where the cutter acts, and a portion to engage the sole in the rear of the point where the cutter acts.
21. In a machine of the class described, a cutter and a gage comprising a portion to contact with the edge of the sole of the shoe being trimmed in the rear of the cutter, a portion to contact with the upper in advance of the cutter, and a detachable member to contact with the edge of the sole in advance of the point where the cutter acts.
22. In a machine of the class described, a cutter and a gage, said gage comprising a contact-surface to engage the edge of the sole in advance of the cutter, and a contact-surface to engage the edge of the sole in the rear of the cutter, said gage being cut away or notched between said contact-surfaces to give clearance for the cutter.
23. In a machine of the class described, a gage having contact-surfaces to engage simultaneously the upper and also the edge of the sole of a shoe being trimmed, and another contact-surface to engage the upper when the toe of the sole is being trimmed.
24. In a machine of the class described, a gage comprising contact-surfaces to engage simultaneously the upper and the edge of the sole of a shoe being trimmed, and a contact-surface intermediate said first-mentioned surfaces and normally out of engagement with the shoe but adapted to engage the upper when the toe of the sole is being trimmed.
25. In a machine of the class described, a cutter and a gage comprising a contact-surface to engage the upper and a contact-surface to engage simultaneously the edge of the sole of a shoe being trimmed, said contact-surfaces being located one in advance of and the other in the rear of the point where the cutter acts on the sole, and another contact-surface intermediate said first-mentioned surfaces to engage the shoe when the toe of the sole is being trimmed.
26. In a machine of the class described, a cutter and a gage comprising a contact-surface to engage the upper of the shoe being trimmed on one side of the point where the cutter acts, and a contact-surface to engage the edge of the sole on the other side of the point where the cutter acts, in combination with a contact-surface located adjacent the point where the cutter acts and adapted to contact with the upper when the toe of the sole is being trimmed.
27. In a machine of the class described, a cutter and a gage comprising contact-surfaces to engage the shoe in front and in the rear of the point where the cutter acts, and another contact-surface intermediate said first-mentioned surfaces and normally out of engagement with the shoe, said intermediate contact-surface being adapted to guide the shoe when the toe of the sole is being trimmed.
28. In a machine of the class described, a cutter and a gage comprising contact-surfaces to guide the shoe while the sides of the sole are being trimmed, and another contact-surface in a different plane from that in which said first-mentioned surfaces are located to guide the shoe while the toe is being trimmed.
29. In a machine of the class described, a cutter and a gage provided with contact-surfaces to engage the shoe being trimmed in advance of and in the rear of the point where the cutter acts, and being provided between said contact-surfaces with a surface located in a higher plane than the said contact-surfaces and adapted to pass over irregularities in the guiding-surface of the shoe without engaging such irregularities, as and for the purpose described.
30. In a machine of the class described, a cutter, a gage comprising guiding-surfaces to contact, one with the upper of the shoe being operated upon and the other with the edge of the sole, when the side edges of the sole are presented to the cutter, said guiding-surfaces being located one in advance of and the other in the rear of the cutter, and another guiding-surface to contact with the upper adjacent the point where the cutter acts when the toe of the sole is being trimmed, said last-named contact-surface being located in a different plane from that in which the first-mentioned surfaces are located, whereby the shoe is guided the desired distance from the cutter while the different parts of the sole are being trimmed.
31. In a machine of the class described, a rotary cutter, a gage, a support for said gage, a stem on said support, means to engage said stem and adjust the gage transversely of the axis of the cutter, and means to clamp said stem to hold the gage in adjusted position.
32. In a machine of the class described, a rotary cutter, a gage, a support for said gage, a stem on said support, means to engage said stem and adjust the gage transversely of the axis of the cutter, and means to clamp said stem to hold the gage in adjusted position, in combination with means to adjust said gage longitudinally of the axis of the cutter.
33. In a machine of the class described, the combination with a rotary cutter, of a support, a gage-carrier angularly adjustable about said support, a gage adjustably sustained by said gage-carrier, and means for securing the gage in adjusted position in the gage-carrier, substantially as described.
34. In a machine of the class described, a gage-carrier, a plurality of gages mounted

thereon, a latch to hold said carrier with one of said gages in operative position, and actuating means operating first to release said latch and then to move said gage-carrier to present a different gage in operative position.

35. In a machine of the class described, a gage-carrier, a plurality of gages mounted thereon, a latch to hold said carrier with one of said gages in operative position, actuating means to release said lock and then to move said gage-carrier to present a different gage in operative position, a returning-spring, and

means to limit the movement imparted by said returning-spring, said limiting means coöperating with said latch to lock said carrier 15 against movement in either direction.

In testimony whereof I have signed my name to this specification in the presence of two subscribing witnesses.

BENJAMIN F. MAYO.
